UNITED STATES PATENT OFFICE.

HERBERT A. CHRISTIAN, OF VALLEJO, CALIFORNIA.

RULE-HOLDER.

1,333,539.

Specification of Letters Patent.

Patented Mar. 9, 1920.

Application filed December 6, 1918. Serial No. 265,586.

To all whom it may concern:

Be it known that I, HERBERT A. CHRISTIAN, a citizen of the United States, residing at Vallejo, in the county of Solano and State 5 of California, have invented new and useful Improvements in Rule-Holders, of which the following is a specification.

The invention relates to rule holders, the object in view being to provide a cheap and 10 efficient article of the character referred to which is insertible in the vest pocket or other pocket of a garment and provided with means for retaining itself in place in said pocket, one of the main features of the invention residing in the guiding shoe or tongue which extends considerably above the pocket when the device is in applied position and which guides the rules into the pocket and between the spring clamping 15 jaws of the device. Such tongue or shoe additionally protects the clothing or garment 20 in conjunction with which the rule holder is used.

With the above and other objects in view, 25 the invention consists in the novel construction combination and arrangement herein fully described illustrated and claimed.

In the accompanying drawings:

Figure 1 is a perspective view of the de- 30 vice.

Fig. 2 is a cross section through the device taken just beneath the clip and looking upwardly.

Fig. 3 is a vertical sectional view illus- 35 trating the rule holder in its applied relation to the pocket of a garment.

The rule holder comprises a pair of oppositely arranged spring rule clamping jaws or members 1 that extend downwardly in con- 40 verging relation and of such length as to reach practically to the bottom of a pocket of a garment. The jaws 1 are connected adjacent to the upper end of the front jaw by means of connecting webs 2 thereby leaving 45 a substantially rectangular pocket 3 through which a measuring rule is insertible as shown in Fig. 3.

The device also comprises a garment hold- 50 ing clip 4 which is resilient, said clip extend- ing from the upper end of one of the jaws 1 downwardly upon the outside thereof, said

clip being adapted to slip over the top of the pocket front wall of a garment in the manner illustrated in Fig. 3. The lower end of the clip 4 is formed with substantially 55 parallel cuts to provide three projecting portions the center one of which is bent downwardly and outwardly to form a thumb piece 5 while the other portions are bent inwardly to provide garment pressing fingers 60 6, the edges of which are preferably toothed or serrated as shown at 7 in order to obtain a firmer grip on the clothing.

Extending upwardly from the rear wall of the pocket 3, and integral with the rear 65 jaw, is a vertical guiding shoe or tongue 8, which is slightly curved and which rests against the body of the garment above the pocket therein as shown in Fig. 3. The shoe or tongue 8 serves to protect the clothing of 70 the wearer and it is made to press more closely against the garment when the spring pressed jaws are spread by the insertion of the rule. The shoe or tongue also serves to 75 guide or direct the measuring rule between the rule clamping jaws 1, the device being held fixedly in its position, in the pocket of the garment by the yieldable or clamping members or jaws supplemented by the means of the clip 4.

The device may be manufactured cheaply 80 out of hard rolled sheet metal to give the required resiliency thereto and may be also manufactured in various sizes to suit different measuring rules.

I claim:

In a device of the class described, the combination of a pair of oppositely located and downwardly converging clamping jaws, oppositely arranged webs connecting said jaws 90 adjacent to the upper end of the front jaw, and a garment engaging clip extending outwardly and downwardly from the upper extremity of the front jaw, said clip being provided at its free end with a centrally ar- 95 ranged projecting thumb piece and also provided at opposite sides of said thumb piece with inwardly extending garment gripping fingers.

In testimony whereof I affix my signature. 100

HERBERT A. CHRISTIAN.
